UNITED STATES PATENT OFFICE.

ERNEST R. GODWARD, OF NEW YORK, N. Y., ASSIGNOR TO THE ECLIPSE PETROL ECONOMIZER SYSTEM COMPANY, LIMITED, OF CHRISTCHURCH, NEW ZEALAND, A CORPORATION OF NEW ZEALAND.

VAPORIZER FOR LIQUID FUELS.

Application filed September 5, 1924. Serial No. 736,024.

This invention relates, generally, to improvements in fuel vaporizers for use in connection with internal combustion engines, and for other uses; and the invention has reference, more particularly, to a novel construction of vaporizing device involving and adapted to apply the general principles of the character of vaporizer apparatus which is shown and described in my United States Letters Patent No. 1,490,919, dated April 22nd, 1924, and in my copending application for Letters Patent filed April 1st, 1924, Serial No. 703,380, but which deals with an improved form of fuel delivery means of a low velocity type.

This invention has for its principal object to provide, in combination with a vaporizing means, a novel construction of low velocity fuel delivering device or nozzle which conducts the charge of liquid hydrocarbon fuel directly into the vaporizing chamber and its coil of plates more efficiently and with less restriction.

Other objects of the present invention deal with a novel arrangement and construction of means for controlling and delivering air for direct cooperation with the novel low velocity fuel delivery device, to produce the primary mixture of fuel and air upon which vaporizing element is to act.

Other objects of this invention, not at this time more particularly enumerated, will be clearly understood from the following detailed description of the same.

The invention is clearly illustrated in the accompanying drawings, in which:-

Figure 1 is a vertical longitudinal section of the novel vaporizer device and its low velocity fuel delivery means made according to and embodying the principles of this invention; Figure 2 is another vertical longitudinal section of the same, taken on line 2-2 in said Figure 1; and Figure 3 is a horizontal section, taken on line 3-3 in said Figure 1.

Figure 4 is a fragmentary vertical longitudinal section of the air intake means for the vaporizer device, illustrating the provision of independent controls for the main air movement or admission and for the auxiliary air admission.

Similar characters of reference are employed in all of the hereinabove described views, to indicate corresponding parts.

Referring now to said drawings, the reference character 8 indicates an outer casing or main body, preferably of cylindrical shape. The interior of said casing or main body 8 is transversely divided by a horizontal partition 9 to provide above the same a vaporizing chamber 10 and beneath the same a heating chamber 11, said partition 9 serving as the hot-plate of the vaporizer elements. Leading into said heating chamber 11 is an intake opening 12, through which a hot fluid may be introduced into said heating chamber, such, for example, as the hot exhaust gases discharged from an internal combustion engine. Leading out of said heating chamber is an outlet opening 13 for discharging the hot fluid from said heating chamber.

Extending centrally upward through the bottom of said casing or main body, to pass through said heating chamber and through the partition or hot-plate 9 is a fuel mixing chamber or passage 14, the discharge outlet of which terminates within said vaporizing chamber 10 above said partition or hot-plate 9. Connected in communication with the lower end of said mixing chamber or passage 14 is an air delivery conduit 15, provided at its outer end with an upwardly directed extension 16, which is positioned at one side and exteriorly of said casing or main body 8.

Arranged within said mixing chamber or passage 14 and the adjoining portions of said air delivery conduit 15 is the novel liquid fuel delivery means, the same comprising a base-block 17 having a threaded shank 18, of reduced diameter, projecting from its lower end, whereby the same may be threaded through the lower wall of the air delivery conduit 15, to thus position said base-block in vertical alignment with the mixing chamber or passage 14. Said base-block 17 is provided in its upper end with a cylindrical cavity, thereby providing an annular upstanding wall or flange 19 at said upper end of said base-block. Supported by said base-block 17, by being telescopically fitted over the same, is an exterior tubular sleeve 20, which projects upwardly into said mixing chamber or passage 14, and supported parallel to said exterior sleeve 20, by being inserted

into said cavity at the upper end of said base-block, is an interior sleeve 21, this arrangement providing an annular space between

the upper free ends of said sleeves 20 and 21, and above the annular wall or flange 19, for retaining a foraminous tubular liquid fuel support 22, the upper end of which projects freely beyond the sleeves 20 and 21 and centrally through the mixing chamber or passage 14 into the vaporizing chamber 10. Said foraminous fuel support 22 may be made by rolling a sheet of wire gauze, of comparatively fine mesh, into a tubular formation. Said base-block 17 is provided with a fuel duct 23, which enters through its shank 18 to extend upwardly therein to meet and communicate with lateral ducts 24, which in turn 15 respectively communicate with vertical ducts 25 extending upwardly through the wall or flange 19 to meet the lower end of said foraminous fuel support 22. Suitably supported exteriorly of said casing or main body 8 is 20 a float chamber 26, of any desired construction, adapted to receive and control the flow of liquid fuel, such as gasoline, to the ducts of said base-block. To the latter end said float chamber is provided with a delivery 25 pipe 27, equipped with an adjustable metering valve 28, said pipe 27 being coupled, in any suitable manner, with said shank 18 of the base-block 17 so as to communicate with the lower end of said fuel duct 23. The exterior sleeve 20 is of smaller diameter than the inside diameter of the mixing chamber or passage 14, thus providing an exterior air passage around said fuel support 22 with which the air delivery conduit 15 communicates. 30 Transverse openings 29 are provided in the wall or flange 19 of the base-block 17, and in the sleeves 20 and 21, whereby air may be delivered from the delivery conduit 15 for passage upwardly through the interior of the sleeve 21 and the foraminous fuel support 22. Secured to said exterior sleeve 20, so as to extend around the same and upwardly around the fuel support 22 through the exterior air passage is a spiral fin 30, whereby the air passing upwardly through the mixing chamber or 40 passage 14 is caused to gyrate or whirl around the external sides of said fuel support 22. If desired, a similar spiral fin 31 supported upon a central core 32 may be arranged within said 45 interior sleeve 21, so as to extend around the inside surface of said fuel support 22, to gyrate the air against the same, as such air passes upwardly through the interior of said fuel support 22. The mechanism thus above 50 described constitutes a very efficient low velocity fuel delivery means for introducing into the vaporizing chamber 10 an initial mixture of liquid fuel and air, the purpose, functions and advantages of which will be 55 subsequently more fully set forth.

Arranged within the interior of said vaporizing chamber 10, so as to surround the discharge end of said mixing chamber or passage 14, and the novel low velocity fuel delivery 60 means with which the same is provided, is a

combined fuel supporting and heat conducting means. This fuel supporting and heat conducting means comprises a plurality of vertical plate sections 33, which are curved from end to end, so that when assembled together they provide a convoluted arrangement radiating outwardly from the center toward the sides of said vaporizing chamber 10. Said plate sections are spaced apart one from another to provide intermediate outwardly leading passages 34, the inner or receiving ends of which converge toward the fuel delivery means, and the outer or discharge ends of which terminate short of the side walls of said casing or main body 8, to thus provide an annular outgoing passage 35. The lower edges of said plate sections 33 are arranged to contact with the partition or hot-plate 9, so as to receive and conduct therefrom its heat. The upper sides of said passages 34 are closed by a top-plate 36 which is engaged upon the upper edges of said assembled plate sections 33.

The upper end of said vaporizing chamber 10 is closed over by a cover-plate 37, which is suitably secured to said casing or main body 8, either by being threaded thereupon, or by any other means or in any other manner found convenient or desirable. Said cover-plate 37 is provided with set-screws 38, which extend downwardly into said vaporizing chamber to engage said top-plate 36 to thereby hold the same and the plate-sections 33 against vertical displacement from the operative assembled relation above described.

In the drawings said plate-sections 33 are, for the purposes of illustration, shown more widely separated than would be the case in practice, and, in fact, the height, number, and spacing of said plate-sections 33 are variable factors, and may be arranged, as to such characteristics, according to the capacity or kind of work to be done, and according to conditions of use.

Connected with said cover-plate 37 is a discharge conduit 39, preferably extending diametrically across the cover-plate. Said discharge conduit 39 is provided with an annular enlargement 40 providing an annular passage 41, which communicates on its under side, through the opening 42, with the interior of the vaporizing chamber 10, and which also opens inwardly throughout its extent into the interior of said discharge conduit 39. Arranged in longitudinal or axial alignment with said discharge conduit 39, and so as to communicate therewith at the rear side of said annular passage 41, is an auxiliary air delivery conduit 43, which communicates at its rearward end with the main air inlet fitting 44. Said main air inlet fitting is provided with a downwardly directed branch 45 which is connected with the upward extension 16 of the main air delivery conduit 15 so as to deliver atmospheric air therethrough. Ar-

ranged in the auxiliary air delivery conduit 43 is an automatic valve means in the form of an expansible conical spring 46. The tension of said spring 46 normally maintains 5 its convolutions closed one upon another, so that said spring provides a normally closed wall or valve device, which opens at high engine speeds to admit auxiliary air for intermixture with the delivered vaporized fuel 10 passing from the vaporizing chamber 10 through the discharge conduit 39 to the engine cylinders. Arranged in the air admission end of said fitting 44 is a suitable throttle or butterfly valve 47, and, in like manner, arranged 15 in the outlet end of said discharge conduit 39 is a throttle valve 48. As shown in Figure 7, if it is so desired, an independently operable throttle or butterfly valve 49 may be provided at the receiving end of said auxiliary air delivery conduit 43 in the rear of 20 said valve spring 46, and in addition to said air admission throttle or butterfly valve 47. In operation a volatile liquid fuel is delivered from the float chamber 26 so as to rise 25 through the ducts 23, 24 and 25 to the lower end of the foraminous fuel support 22, through which, by reason of its foraminous structure, the same tends to rise and be supported by capillary attraction, so as to be exposed 30 to the air stream delivered through the passage 14. It will be quite evident that the foraminous fuel support provides a comparatively large surface area, which holds the liquid fuel in suspension, while under the effects 35 of partial vacuum or unbalanced pressure induced by the suction strokes of the internal combustion engine served by the vaporizer. Atmospheric air, when pressure is reduced within the vaporizer by the suction 40 strokes of the internal combustion engine, enters through the inlet fitting 44 and passes through the main air delivery conduit 15 to the lower end of the mixing chamber or passage 14 to flow upwardly therethrough around 45 the foraminous fuel support 22. A portion of the air thus caused to flow in contact with the surface of said foraminous fuel support may, if desired, be admitted through the openings 29 to pass upwardly through the interior 50 of the said fuel support in contact with its inner surface. In order to produce a more effective frictional sweep of the air in contact with the surfaces of the fuel support, I prefer to provide the spiral fins 30 and 31 which 55 cause the air streams to whirl or gyrate around the surfaces of said fuel support with a centrifugal action which more effectively draws or forces away from the surfaces of the fuel support the particles of liquid fuel suspended 60 or supported thereon, so that the same will readily be taken up by the air notwithstanding the comparatively low velocity of movement of the latter due to the absence of marked or pronounced restriction at any point 65 in the air passages. Such an arrangement is highly efficient in combination with the vaporizing means through which the mixture of air and liquid fuel is subsequently passed, for the reason that the fuel support provides a comparatively large supporting area 70 upon which is temporarily mechanically supported a multiplicity of minute particles of liquid fuel which readily leave the support, under the friction of the air current, so as to enter into and be conveyed by the air into the vaporizing chamber, notwithstanding the comparatively low velocity of movement of the air. Thus instead of having a single nozzle at the mouth of which but a small exposure of the liquid fuel is inertly supported 75 so that a high velocity of air movement is required to dislodge it and thus cause the same to be taken up into the air stream, my arrangement provides what may be said to be equivalent to hundreds of jets according to 80 the mesh of the gauze (e. g. 100 per square inch) or fineness of the porosity afforded by its foraminous character, and the area of surface exposed to the air stream. Furthermore, this multiplicity of so called jets provided 85 by the foraminous fuel support will readily yield up to the air the many minute particles of liquid fuel so long as the surface of the support is exposed to the partial vacuum, since the tension of the liquid or tendency to cling 90 is greatly reduced when subjected to pressures less than that of the atmosphere, for under such circumstances the liquid fuel will tend to spread out and thin itself in the meshes or pores of the foraminous support so that 95 the friction of the passing air will readily dislodge it, especially when the air is caused to gyrate or swirl as well as to advance along the surface of said support. The mechanical mixture of liquid fuel and air is therefore delivered, with the least possible amount of restriction, so that larger volumes of air passing 100 through comparatively large and free air conduits may be utilized to the end that a required volume of intermixed fuel and air 105 may be continuously discharged into the vaporizing chamber, wherein the liquid content of the charge is vaporized to produce a substantially dry and correct combustible fuel 110 at all engine speeds. So far as the operation and function of the plate-sections 33, and other elements and arrangements comprising the vaporizing chamber, are concerned, the same are in accord with and conform to the disclosures of my aforementioned prior 115 United States patent and co-pending application for United States patent. 120

The vaporized combustible fuel is drawn by the induction strokes of the engine pistons from the vaporizing chamber 10 into the annular passage 41 through the opening 42, and thence pass through the discharge conduit 39 through the engine intake manifold leading to the engine cylinders. At high engine speeds it is desirable that the combusti- 125 130

ble fuel be comparatively cool upon entering the engine cylinders, which is best accomplished by increasing the ratio of air volume to gasified fuel, consequently I have provided 5 the expansible valve spring 46 intermediate the main air-inlet 44 and the gasified fuel passage 41 arranged between the vaporizing chamber 10 and discharge conduit 39, whereby the control and direct admission of an 10 additional volume of atmospheric air is automatically attained. The operation is such that the increased suction activity of the engine pistons will reduce the pressure within the discharge conduit 39 so that the atmospheric pressure behind the valve spring 46 15 will expand or distend the same, thus separating its coils and allowing additional air to rush through directly into the discharge conduit 39 to mix with the combustible fuel 20 discharging therethrough. An incidental effect of the particular manner of thus introducing said auxiliary air is that the inrushing of the stream of the latter into the rear end of the discharge conduit 39 has an inspirational effect tending to increase the 25 speed of flow of the combustible fuel from the vaporizer into and through the discharge conduit under such circumstances. It will be obvious that the initial control of both the 30 main air and auxiliary air for passage through the apparatus may be accomplished by manipulation of the butterfly valve 47, and, if desired, independent initial control of the auxiliary air may be accomplished by providing and manipulating the auxiliary butterfly valve 49.

It will be noticed that the air delivery conduit 15 possesses the upstanding extension 16 parallel to the liquid fuel mixing elements 40 and the vaporizing elements. This arrangement provides a reserve well into which the vaporized or gasified fuel will descend, and by which it will be retained when the engine is idle, because of the fact that its specific

gravity is in excess of that of the atmosphere; 45 consequently there is always reserved a volume of such fuel for starting purposes.

Having thus described my present invention, I claim:—

1. In a vaporizing device, means operative 50 under low air velocity for producing an initial mixture of liquid fuel and air for delivery thereto, comprising an air intake member providing a substantially tubular passage arranged to receive air at its lower end, a foraminous liquid fuel support of tubular form 55 concentric to and axially disposed within said air intake member, a liquid fuel delivery means in which the lower portion of said fuel support is submerged and by which it is in 60 turn supported, and said liquid fuel delivery means also having air admission means leading into the interior of said fuel support from said air intake member whereby the air stream delivered through the latter simultaneously moves in part through the interior and in part around the exterior of said fuel support, an internal spiral fin cooperative 65 with the inner surface of said fuel support, and an external spiral fin cooperative with 70 the outer surface of said fuel support.

2. In a device of the kind described, a foraminous tubular fuel support, means for delivering liquid fuel to the lower portion of 75 said support for capillary movement therethrough, and means for delivering air streams simultaneously in contact with both the interior and exterior exposed surfaces of said fuel support, and means cooperative with both the inner and outer surfaces of said 80 fuel support for producing a centrifugal movement of said air streams in contact therewith.

In testimony, that I claim the invention set forth above I have hereunto set my hand this 85 3rd day of September, 1924.

ERNEST R. GODWARD.
